DESIGN FOR A FOOTED EPERGNE OR ARTICLE OF SIMILAR NATURE

T. Clarence Heisey, Newark, Ohio, assignor to
A. H. Heisey & Company, Newark, Ohio

Application May 25, 1949, Serial No. 2,861

Term of patent 14 years

(Cl. D48—2)

To all whom it may concern:

Be it known that I, Thomas Clarence Heisey, a citizen of the United States of America, and a resident of Newark, in the county of Licking and State of Ohio, have invented a new, original, and ornamental Design for a Footed Epergne or Article of Similar Nature, of which the following is the specification, reference being had to the accompanying drawing, forming a part thereof.

Figure 1 is a side elevational view of a footed epergne or article of similar nature, showing my new design.

Figure 2 is a fragmentary cross-sectional view taken along line 2—2 of Figure 1, and

Figure 3 is a perspective view,

I claim:

The ornamental design for a footed epergne or article of similar nature, substantially as shown.
T. CLARENCE HEISEY.
